UNITED STATES PATENT OFFICE.

STUART E. FREEMAN, OF ST. LOUIS, MISSOURI.

VAPOR-BURNER.

SPECIFICATION forming part of Letters Patent No. 674,578, dated May 21, 1901.

Application filed April 16, 1900. Serial No. 12,995. (No model.)

To all whom it may concern:

Be it known that I, STUART E. FREEMAN, a citizen of the United States, residing at the city of St. Louis, in the State of Missouri, have

5 invented certain new and useful Improvements in Vapor-Burners, of which the following is a full, clear, and exact description, reference being had to the accompanying drawings, forming part of this specification.

10 My invention relates to a burner used in the consumption of hydrocarbon oils to create heat, and has for its object the construction of a burner in which the supply of vapor admitted to the burner is regulated by the demands of the apparatus that is heated in the 15 operation of the burner and in which a pilot or jet pipe is maintained in constant operation to serve ignition purposes whenever the heated apparatus becomes depleted of sufficient heat to require the re ignition of the burner *in toto*.

My invention consists in features of novelty hereinafter fully described, and pointed out in the claims.

25 Figure I is a top or plan view of my improved burner. Fig. II is a front elevation, partly in vertical section, taken on the line II II, Fig. I. Fig. III is a longitudinal section of the controller.

30 1 designates a frame in which the burner is contained, said frame being preferably of metal.

2 designates a conveyer-pipe through which hydrocarbon oil may be supplied to the 35 burner, said pipe being equipped with a valve 3. The oil-pipe 2 communicates with a generator-pipe 4, that extends in the form of a rectangle, as seen in Fig. I, within the frame 1. The generator-pipe 4 communicates with

40 a vapor-conveying pipe 5, that leads to a position exterior of the frame 1. The vapor-conveying pipe 5 has a lateral extension 5^a, which enters a controller 6, provided with a valve that is governed by a pressure medium 45 to control the escape of vapor therefrom according to the pressure supplied thereto through a pressure-medium pipe 7, that leads from the apparatus that is heated by the burner. No invention is herein claimed for 50 the controller 6 *per se*, a brief description of which is hereinafter given.

The vapor generated in the generator-pipe

4 passes through the vapor-conveying pipe 5 and lateral extension 5^a to the controller 6 and is discharged therefrom into the mixing- 55 tube 8 to be commingled with air.

9 designates a manifold into which the vapor is discharged through the mixing-tube 8, and 10 is an equalizing-manifold arranged parallel to the manifold 9, but remote therefrom. The manifolds 9 and 10 are connected by a series of burner-tubes 11, provided in their upper edges with slits 12, said tubes having free communication with the interior of the manifolds 9 and 10 to permit the ready 65 passage of vapor from the manifold 9 into said tubes for escape directly therefrom through slits 12 or to the manifold 10, in which the vapor is equalized and from which it returns to the burner-tubes. 70

13 designates a trough located within the frame 1 beneath the inner part of the generator-pipe 4, this trough being preferably filled with asbestos or other non-combustible substance and adapted to receive a quantity of 75 hydrocarbon oil or inflammable spirit that upon being ignited will diffuse its heat into contact with the pipe 4 above it and impart heat to said pipe to create initial generation of vapor from the hydrocarbon oil entering 80 said pipe from the supply-pipe 2 on the opening of the valve 3. The trough 13 extends through the wall of the frame 1 to the exterior thereof for convenience in lighting the inflammable oil or spirit placed therein. 85

14 designates a pilot or jet pipe extending across the burner-tubes 11 and around the generator-pipe 4 above the trough 13. This pilot or jet pipe is provided with a series of small jet-holes throughout its length, including the portion of it which encircles the generator-pipe 4, (see Fig. II,) and is connected to the generator-pipe 4 at 15. (See Fig. I.) The vapor escaping from the jet-holes in the pipe 14 is initially ignited at the end of said pipe 95 extending above the trough 13, and the vapor escaping from the other jet-openings throughout said pipe is ignited by the flame of each jet communicating to the next succeeding jet throughout the length of the tube. As the 100 vapor is ignited at each jet-opening the vapor escaping from the burner-tubes 11 through the slits 12, arranged in proximity to said jet-openings, becomes ignited from the jets of

flame, the burner being thereby quickly lighted throughout its extent. When the pressure medium flowing through the pipe 7 becomes sufficient to actuate the controller 6 and shut off the passage of vapor therethrough from the pipe 5, the supply of vapor to the manifolds 9 and 10 and the burner-tubes 11 is cut off, extinguishing the flames previously burning at said burner-tubes, the jet or pilot pipe 14 receiving its supply direct from the generator-pipe 4 at such time continues to receive the vapor from the generator-pipe, and such vapor remains ignited at the jets of said pipe 14. When the pressure medium entering the controller 6 through the pipe 7 becomes lowered to normal condition, the passage-way through the controller is again opened for the flow of vapor therethrough to the manifold 9 and into the burner-tubes 11. The vapor then escapes, as before, through the slits in the burner-tubes and is quickly ignited from the jets of flame burning from the pipe 14. During the period that the flames are unlighted at the burner-tubes the pilot-pipe 14 is supplied with vapor that is generated in the generator-pipe 4 at the location of the pilot-pipe where it encircles said generator-pipe and by reason of the jets burning from the pilot-pipe at this position. Furthermore, the heat received by the various parts of the burner, including the inclosing frame 1, in the operation of the burner at full service is retained for a considerable period, and after the flame at the burner is extinguished by the operation of the controller the heat radiates from the surrounding parts of the burner to the generator-pipe and lends assistance in maintaining a heated condition of said generating-pipes to vaporize the oil passing thereto.

The frame 1 is provided with a central aperture 1^a in its bottom (see Fig. II) through which air may enter the frame to pass upwardly through the spaces between the burner-tubes 11 to supply the requisite amount of oxygen for the proper combustion of the vapor. In a burner of this description it is also necessary that the burner-tubes be located in as close assemblage as possible consistent with sufficient interior area therein to receive as much vapor as will properly mix with the air supplied. In order to obtain the desired results, I construct the tubes 11 of oval shape in cross-section, which permits of their close assemblage, while at the same time it permits the passage of air between them and provides a maximum of interior area.

The controller 6 contains a pair of diaphragms 6^a, between which is located a valve 6^b, that governs a passage between two chambers inclosed by the diaphragms. The valve 6^b is normally held from its seat by a spring 6^c. Under normal conditions the vapor enters the controller through the lateral extension 5^a of the vapor-conveying pipe 5 and passes through the first chamber past the valve 6^b into the second chamber and escapes to the

burner through the outlet 6^d. An excess of pressure medium entering the controller through the pipe 7 presses against the diaphragm at the end of the controller to which the pipe 7 is connected and carries the valve 6^b to its seat against the action of the spring 6^c, thereby shutting off the passage of vapor through the controller to the outlet until such time as the pressure medium becomes lowered.

I claim as my invention—

1. In a vapor-burner, the combination of a generator-pipe in the form of a rectangle, a controller to which said pipe is connected, burner-tubes surrounded by the generator-pipe, a manifold with which the burner-tubes are connected and to which the vapor is delivered from said controller, and a pilot or jet pipe connected to said generator-pipe, and extending across the burner-tubes and adapted to convey lighting medium thereto, substantially as described.

2. In a vapor-burner, the combination of burner-tubes, a manifold having communication with said burner-tubes, a generator-pipe in the form of a rectangle surrounding the burner-tubes, a controller connected to said generator-pipe, and having an outlet arranged in communication with said manifold; and a pilot or jet pipe arranged in proximity to and extending across said burner-tubes, substantially as described.

3. In a vapor-burner, the combination of burner-tubes, a pair of manifolds having communication with said burner-tubes, a generator-pipe in the form of a rectangle surrounding the burner-tubes, a controller connected to said generator-pipe, and a pilot or jet pipe arranged in proximity to and extending across said burner-tubes, substantially as described.

4. In a vapor-burner, the combination of burner-tubes, a manifold having communication with said burner-tubes, a commingling-tube, a generator-pipe in the form of a rectangle surrounding the burner-tubes, a controller connected to said generator-pipe arranged to discharge through said commingling-tube into said manifold, a lighter-trough arranged beneath said generator-pipe, and a pilot or jet pipe arranged across said burner-tubes and said lighter-trough, substantially as described.

5. In a vapor-burner, the combination of a frame, a pair of manifolds located in said frame, burner-tubes connecting said manifolds and having communication therewith, a commingling-tube, a generator-pipe surrounding the burner-tubes, a controller connected to said generator-pipe and arranged to discharge through said commingling-tube into one of said manifolds, and a jet-pipe arranged across said burner-tubes, substantially as described.

6. A vapor-burner comprising a frame, a conveyer-pipe having a controlling-valve, the generator-pipe in the form of a rectangle with which the conveyer-pipe is connected, the vapor-conveying pipe leading from the genera-

tor-pipe beyond the frame and having a lateral extension, a controller with which the lateral extension is connected, a commingling-tube into which the controller discharges, the 5 outer manifold with which the commingling-tube is connected, the inner manifold, the series of burner-tubes surrounded by the generator-pipe and connecting the manifolds, and the jet-pipe extending from the vapor-conveying pipe beneath and over the outer part 10 of the generator-pipe adjacent thereto and across the burner-tubes.

7. A vapor-burner comprising a frame, a conveyer-pipe having a controlling-valve, the 15 generator-pipe in the form of a rectangle, with which, the conveyer-pipe is connected, the vapor-conveying pipe leading from the generator-pipe beyond the frame and having a lateral extension, a controller with which the 20 lateral extension is connected, a commingling-tube into which the controller discharges, the outer manifold with which the commingling-tube is connected, the inner manifold, the series of burner-tubes oval in cross-section for 25 close assemblage and connecting the manifolds and surrounded by the generator-pipe, and the jet-pipe extending from the vapor-

conveying pipe beneath and over the outer part of the generator-pipe adjacent thereto and across the burner-tubes.

8. A vapor-burner comprising a frame, a conveyer-pipe having a controlling-valve, the generator-pipe in the form of a rectangle with which the conveyer-pipe is connected, the vapor-conveying pipe leading from the generator-pipe beyond the frame and having a lateral extension, a controller with which the lateral extension is connected, a commingling-tube into which the controller discharges, the outer manifold with which the commingling-tube is connected, the inner manifold, the series of burner-tubes connecting the manifolds and surrounded by the generator-pipe, the jet-pipe extending from the vapor-conveying pipe beneath and over the outer part 40 of the generator-pipe adjacent thereto and across the burner-tubes, and the initial heating-trough located beneath the outer part of the generator-pipe and extending beyond the front of the frame.
